Primary Examiner — John Windmuller*Assistant Examiner* — John R Yeh(74) *Attorney, Agent, or Firm* — Patrick J. Hofbauer; Kevin E. Holbeche(57) **CLAIM**

The ornamental design for a clip for light socket, as shown and described.

DESCRIPTION

FIG. 1 is a top and front facing, right perspective view of our new design;

FIG. 2 is a further top and front facing, right perspective view thereof;

FIG. 3 is a bottom and rear facing, left perspective view thereof;

FIG. 4 is a side elevational view thereof;

FIG. 5 is a front elevational view thereof;

FIG. 6 is an opposing side elevational view thereof;

FIG. 7 is a rear elevational view thereof;

FIG. 8 is a top plan view thereof; and,

FIG. 9 is a bottom plan view thereof.

The broken lines in FIG. 1 showing a light bulb, a light socket and electrical wires are for the purpose of illustrating environmental structure and form no part the claimed design.
